UNITED STATES PATENT OFFICE

1,997,113

SAFE PROTECTOR

Thomas N. Lewis, St. Louis, Mo.

Application September 8, 1934, Serial No. 743,295

8 Claims. (Cl. 109—6)

This invention relates to devices used for protecting the combination locks of bank vaults and safes and has as its object the provision of a device which will frustrate burglars when the latter, as is the usual practice when the combination lock cannot be mastered, attempt to knock off the knob of the permutation lock and drive the spindle inwardly, thereby moving the lock tumblers in the safe out of line with the dog or fence, and release the locking engagement of the bolt stop with the bolt of the lock; there being provided in accordance with the present invention, means operable to discharge an obnoxious gas as soon as an effort is made in the manner just described to unauthoritatively enter the safe or bank vault.

10

The invention, together with its objects and advantages, will be best understood from a study of the following description taken in connection with the accompanying drawings wherein:

20

Figure 1 is an elevational view of the device applied.

Figure 2 is a perspective view of a slide member.

25 Figure 3 is a plan view of a gas containing tube, parts thereof being broken away and shown in section.

Figure 4 is a transverse sectional view through the device in applied position; the gas tube being omitted.

30 Figure 5 is a fragmentary view partly in section and partly in elevation illustrating certain details of construction to be hereinafter more fully referred to.

35 Figure 6 is a vertical sectional view.

Figure 7 is a similar view taken at right angles to Figure 6.

40 Figure 8 is a fragmentary plan view showing the eccentric pin arrangement of the device.

45 Referring to the drawings by reference numerals, it will be seen that 10 designates a circular casing of frangible material having an open side to which is secured a plate 11 having an integral formation 11' formed thereon and recessed as at 12 to accommodate the dial 13 of the permutation lock with which the vault or safe 14 is equipped; said formation at the inner end of the recess 12 being also provided with an opening 15 to accommodate the knob 16 of the permutation lock as clearly shown in Figure 4. At the open side thereof the casing 10 is provided with an inwardly directed flange 17 whereby through the medium of screws or other fastening devices 18 the plate 11 is secured to the casing.

50 55 A disk 19 of suitable material has a reduced

portion 19a rotatable in an opening 20 provided in an end wall of the casing 10. For the disk 19 there is provided a knob 21 that engages the outer face of the end wall of the casing 10 and is secured to the disk 19 by screws or the like 22, the disk 19 and knob 21 being secured in this manner cooperating to retain the disk in operative position.

5 The disk 19 is also provided with a hollow hub 23 that terminates in slightly spaced relation to the end wall of the recess 12. The hub 23 of the disk is also slotted as at 24 for slidably accommodating a slide 25 provided on one edge with ratchet teeth 26, springs 45 yieldingly retaining the slide in retracted position.

10 On the inside of the end wall of the casing 10 there is a stop lug 27 and to accommodate the lug the disk 19 is formed with an arcuate groove or slot 28 the ends of which form shoulders 29

15 and 29' that engage the lug 27 for limiting rotational movement of the disk. Lug 27 is provided with ratchet teeth 30 cooperable with the teeth of the slide 25 in a manner to lock the disk 19 against rotation.

20 For operating the slide 25 there is provided in the knob 21 of the disk a conventional key-operated lock 31 the rotating tumbler of which is provided with an eccentric pin 32 that operates in a D-slot 33 provided in the slide 25 intermediate the ends of the latter, as clearly shown in Figure 5. Manifestly by placing the key 34 in the lock 31 and rotating the tumbler thereof, the slide 25 will be projected or retracted according to the direction of rotation of the tumbler and as it is desired to lock or release the disk 19.

25 30 35 For releasably securing the device in place, there are pivoted to the end wall of the recess 12 at circumferentially spaced points, dogs 35 that are normally urged by suitably mounted springs 36 radially outwardly with respect to the center of the device and the neck of the knob 16. Adjacent their free ends the dogs are provided with laterally extending pins on which are journaled rollers 37 that are engaged by cam humps 38 formed on the inner edge of a ring 39 secured to the inner side of the disk 19 by screws 40 and spaced from the disk by sleeves 41 disposed on the screws between the ring and the disk as clearly shown in Figure 4.

40 45 50 55 From the above it will be apparent that normally the cams 35 are in spread or radially outward position. When in this position, the casing and associated parts are slipped over the knob 16 and dial 13 of the combination lock. The knob 21 is then turned to rotate the disk in a counter-

clockwise direction as viewed in Figures 5 and 6. Rotation of the disk will, through the medium of the cams 38 engaging the rollers 37, force the dogs 35 against the action of springs 36 radially inwardly to engage the neck of the knob 16 in a manner to secure the device in position. Also, and as is obvious, the disk 19 will rotate in the direction just mentioned until the shoulder 29 is brought into engagement with the lug 27 when the key 34 is turned to project the slide 25 aligned with the lug 27 resulting in an inter-engagement of the teeth 26 and 30. The key 34 is then withdrawn whereupon the device is left in position with the disk 19 secured against unauthorized rotation to release the device.

Arranged within the casing 10 is a circular or doughnut-shaped tube 42 of frangible material, such as glass, and as shown the tube fits concentric to the recess 12 and the disk 19. Sealed within the tube is a gas 43, commonly known in the art as "tear gas" and consisting of a suitable mixture of chloracetophenone and chloropicrin in liquid form, and which, as is well known, evaporates very quickly liberating a cloud of the well-known "tear-gas".

It will thus be apparent that with the device secured in position as above described, should an attempt be made to disturb the locked condition of a safe, and in so doing the burglar attempt to pry off the casing 10, the tube 42 will be broken or fractured, resulting in making an exit for the gas, and as is obvious, upon liberation of the gas the cracksmen will be driven away or disabled.

What is claimed is:

1. In combination with a lock having a dial and a knob, means for protecting the lock against unauthorized access to the knob or dial, said means comprising a casing, key-controlled cam-actuated means for detachably locking the casing to the knob with the casing concealing the knob and dial, and an annular tubular vessel of frangible material, charged with a toxic fluid, arranged within the casing.

2. In a device for protecting a permutation lock against unauthorized opening, a casing of brittle material, means for detachably locking the casing to the lock to conceal the knob and dial of the lock, said means including pivoted elements engageable with the lock to secure the casing thereto, and key-controlled, cam-actuated means for securing the pivoted element against unauthorized release.

3. In a device for protecting a permutation lock against unauthorized opening, a casing adapted to receive the knob of the lock, pivoted locking dogs within the casing engageable with the knob for detachably locking the casing to the lock, means for moving the dogs into and out of engagement with the knob of the lock, and a vessel of frangible material, charged with a toxic fluid, arranged within the casing.

4. In a device for protecting a permutation lock against unauthorized opening, a casing of brittle material, pivoted elements arranged within the casing to engage the knob of the lock to detachably secure the casing on the lock, a rotary actuator arranged in the casing, means operatively connecting the actuator with the pivoted members for moving the latter into locking engagement with the knob of the lock, and key-controlled means for securing the actuator against unauthorized rotation.

5. In a device for protecting a door against unauthorized opening, a casing, having an end plate provided with a recess to accommodate the dial of the lock, and an aperture for the passage of the knob of the lock into the casing, means for detachably locking the casing to the knob of the lock, and a doughnut shaped tube of frangible material arranged within the casing and charged with a toxic fluid.

6. In a device for preventing unauthorized tampering with a permutation lock, a casing provided with an end plate having a recess to accommodate the dial of the lock and an aperture to accommodate the knob of the lock and permit the casing to be slipped onto the lock, a series of pivoted dogs arranged within the casing and adapted to be moved into engagement with the knob for releasably locking the casing to the lock, rotary cam means within the casing and engageable with the dogs for moving the latter into engagement with the knob of the lock, actuator means for said cam means, and means internally of the casing holding a charge of gas or gas-producing liquid whereby unauthorized removal of the casing from the lock will cause a liberation of the gas charge.

7. In a lock protecting device, a casing surrounding the controlling element of a lock mechanism, key-controlled, pivoted element mounted internally of the casing engageable with the controlling elements of the lock mechanism for releasably locking the casing thereto, and a doughnut-shaped tube, charged with a gas or gas-producing fluid arranged within the casing and surrounding the said controlling element of the lock mechanism.

8. In a lock protecting device, a mounting casing surrounding the controlling elements of a lock mechanism, locking dogs pivotally mounted in the casing and engageable with the controlling elements for releasably locking the casing thereto, an actuator rotatably mounted in the casing, interengaging means on the actuator and the dogs for moving the latter into engagement with the said controlling elements of the lock mechanism, a knob for the actuator, key-controlled means arranged in the knob for locking the actuator against unauthorized operation, and frangible means within the casing, charged with a gas or gas-producing fluid.

THOMAS N. LEWIS.
